Des. 185,841

Patented Aug. 11, 1959

185,841

ROAD ROLLER

Harry Schertzer, Newton, Mass.

Application March 13, 1958, Serial No. 50,015

Term of patent 14 years

(Cl. D14—3)

FIG. 1

FIG. 2

FIG. 3

Figure 1 is a perspective view of a road roller looking towards the right-rear, embodying my new design.

Figure 2 is a perspective view looking towards the left-front.

Figure 3 is a top plan view thereof.

I claim:

The ornamental design for a road roller, as shown.
